UNITED STATES PATENT OFFICE.

GEORGE S. LORD AND JAMES AFFLECK, OF CHICAGO, ILLINOIS.

WINDOW-FASTENER.

No. 828,037.

Specification of Letters Patent.

Patented Aug. 7, 1906.

Application filed December 29, 1905. Serial No. 293,841.

To all whom it may concern:

Be it known that we, GEORGE S. LORD and JAMES AFFLECK, citizens of the United States, residing at Chicago, in the county of Cook and State of Illinois, have invented certain new and useful Improvements in Window-Fasteners, of which the following is a specification.

This invention relates to improvements in sash-fasteners of that type comprising two hinged sections, one of which is rigidly secured in position upon the upper sash, while the opposite section is provided with stop-flanges to engage with the lower sash and either limit the amount the window can be opened or lock it in a closed position.

The principal object of the invention is to provide means for locking or securing a window which has been left partly open for the purpose of ventilation.

A further object is to so construct a fastener of this kind as to enable it to be cheaply manufactured from sheet metal and readily applied to any window.

For a full description of the invention and the merits thereof and also to acquire a knowledge of the details of construction of the means for effecting the result reference is to be had to the following description and accompanying drawings, in which—

Figure 1 is a perspective view showing the application of the device. Fig. 2 is a detail perspective view of the fastener. Fig. 3 is a plan view of the fastener before the flanges are bent into position.

Corresponding and like parts are referred to in the following description and indicated in all the views of the drawings by the same reference characters.

The sash-fastener comprises, essentially, two approximately rectangular plates 1 and 2, which may be formed of sheet metal and are hinged together at 3 along one of the longitudinal edges. The plate 1 is preferably somewhat longer than the plate 2 and is provided with a series of countersunk screw or nail openings, by means of which it is secured in position upon the upper sash. The opposite plate 2 is provided near its upper end with a transverse cut 4, which extends inwardly toward the hinge 3 and has communication at its inner end with an upwardly-extending longitudinal cut 5. The portion of the plate 2 above the cut 4 is bent outwardly at approximately right angles to the plate 2 to form an outwardly-projecting

flange 6, and the lower portion of the flange 6 adjacent to the cut 5 is bent upwardly to form a stop-flange 7. A portion is cut away from the lower end of the plate 2 and adjacent to the hinged member 3. This cut-away portion is shown as being rectangular in shape, and a small leaf 8 fits within said opening and is hinged to the plate 1. This leaf 8 is adapted to move independently of the plate 2 and is provided at its lower end with an extension which is bent outwardly to form the stop-flange 9.

In the operation of the device the plate 1 is secured to the right-hand stile of the upper sash 10 immediately over the lower sash 11, so that the stop-flange 9 can be swung over the top of the lower sash and lock the window in a closed position. When it is desired to open the window a limited amount for ventilating purposes, the leaf 8 is swung around so that the stop-flange 9 projects into the glass-receiving opening. The lower sash 11 can then be raised or the upper sash 10 lowered until the upper stop-flange 7 comes into contact with the top of the lower sash 11. When the plate 2 and leaf 8 are both turned so that the stop-flanges 7 and 9 project into the glass-receiving opening in the upper sash, it will be evident that either window-sash can be raised or lowered as far as the casing will permit.

The plate 1 is preferably made somewhat longer than the plate 2, as shown in the drawings, in order to prevent any one from boring a hole through the window-sash and opening the fastener with a wire or similar device.

While the fastener is illustrated as adapted to be applied to the right-hand side of the upper sash, it will be understood that with slight modifications it might also be placed upon the opposite side of the sash.

Having thus described the invention, what is claimed as new is—

1. A sash-fastener comprising a fixed plate, a second plate hinged to the fixed plate, an outwardly-extending stop-flange projecting from the second plate, and a third member serving as a stop and hinged to the first-mentioned plate so as to operate independently of the second plate.

2. A sash-fastener comprising a fixed plate, a second plate hinged to the fixed plate, an outwardly-extending flange projecting from the second plate, a stop-flange projecting from the said flange, and a third member serving as a stop and hinged to the fixed

plate so as to operate independently of the second plate.

3. In a sash-fastener, the combination of a fixed plate, a second plate hinged thereto and provided with a transverse cut having communication at its inner end with a vertical cut, the portion of the plate above the transverse cut being bent at approximately right angles to the second plate to form an outwardly-projecting flange, and the lower portion of said flange adjacent the vertical cut being bent upwardly to form a stop-flange, a

leaf pivoted to the fixed plate and operating in a space formed by cutting away a portion of the second-mentioned plate, and a stop-¹⁵ flange projecting from said leaf.

In testimony whereof we affix our signatures in presence of two witnesses.

GEORGE S. LORD. [L. S.]
JAMES AFFLECK. [L. S.]
